UNITED STATES PATENT OFFICE.

WILLIAM BELSKY, OF NEW YORK, N. Y., ASSIGNOR TO PARAGON BUTTON CORPORATION, OF NEW YORK, N. Y., A CORPORATION OF NEW YORK.

BUTTON CLAMP.

Application filed November 12, 1923. Serial No. 674,331.

To all whom it may concern:

Be it known that I, WILLIAM BELSKY, a citizen of the United States, and a resident of the city of New York, Queens, borough of Queens, in the county of Queens and State of New York, have invented a new and Improved Button Clamp, of which the following is a full, clear, and exact description.

10 The present invention relates to new and useful improvements in buttons, and it pertains more particularly to a button for use in connection with button-sewing machines.

15 It is one of the primary objects of the invention to provide a button which is so constructed that it will be automatically positioned with respect to a holder of the button-sewing machine.

20 It is a further object of the invention to construct a button in such a manner that it will be held in such a manner that the needle of the button-sewing machine will pass through the thread openings in the button.

25 With the above and other objects in view, reference is had to the accompanying drawings, in which—

Figure 1 is a top plan view of a holding attachment for button-sewing machines, showing a button constructed in accordance 30 with the present invention in place thereon;

Fig. 2 is a sectional view thereof taken on the line 2—2 of Fig. 1;

Fig. 3 is a sectional view thereof taken on the line 3—3 of Fig. 1;

35 Fig. 4 is a sectional view of a modified form of the invention;

Fig. 5 is a sectional view of the modified form shown in Fig. 4, and taken at right angles to such figure;

40 Fig. 6 is a perspective view of the button.

Referring more particularly to the drawings, the button holder comprises a pair of foot members 10, and positioned above said foot members 10, there is a pair of resilient

45 spring fingers 11. Each of these spring fingers 11 has an offset head portion 12, and each of said offset head portions 12 is bent downwardly as at 13, to form a projecting nose or the like, 16.

50 The reference numeral 20 designates a button, and such button is provided with thread openings 21 which pass therethrough

as is common in the art. The body of the button, however, is provided with an elongated recess or groove 22 which extends preferably entirely across the face of the button, the thread openings 21 being spaced with respect to the peripheral edge of the button in the bottom wall of the groove or slot 22 formed therein. By this construction, when the button is inserted beneath the offset portions 12 of the spring fingers 11, the projections 16 will extend into the slot or groove 22, to position a button relative to the holder and maintain the same in this position until the sewing operation is finished.

55 In that form of the invention shown in Figs. 4 and 5 the button is distinguished from the button shown in the form of the invention illustrated in Figs. 1 to 3, inclusive, in that the channel or groove 22 with which the button is provided is formed on the under face of the button, as shown at 25 in Figs. 4 and 5. In this form of the invention the foot members 10 are indented as 60 shown at 26, to provide upwardly extending projections 27 adapted to be received within the channel 25 to maintain the position of the button during the sewing operation. This construction permits of the face of 65 the button being provided with a suitable design or ornamentation which is not broken or interrupted by the channel, the latter being formed upon the back of the button rather than upon the face as in the first 70 described form of the invention.

75 From the foregoing it is apparent that the present invention provides a button which may be readily inserted and properly positioned with respect to the button holder of button-sewing machines, and that by the construction of the button the same is maintained against accidental displacement relative to the holder, thus insuring registration of the needle openings of the button 80 with the path of travel of the needle.

85 What is claimed is:

1. In a button-sewing machine, a button-holding means, said button-holding means comprising a pair of oppositely disposed 90 resilient fingers and a projection formed on each of said resilient fingers and adapted to extend into a recess formed in the button between the holes of the button and the periph-

ery thereof, to hold the button in position during the sewing operation.

2. In a button-sewing machine, a button-holding means comprising a foot, and a plurality of spring fingers adapted to overlie the foot and in spaced relation to each other, said spring fingers having depressed por-

tions forming projections adapted to be received within a recess formed in the button between the holes of the button and the periphery thereof to prevent movement of the button relative to the button-holding means during the sewing operation. ¹⁰

WILLIAM BELSKY.
